UNITED STATES PATENT OFFICE

171,382

FISHING ROD HOLDER BELT

Robert J. Brown, Los Angeles, Calif.

Application November 8, 1952, Serial No. 22,210

Term of patent 14 years

(CL. D3—10)

To all whom it may concern:

Be it known that I, Robert J. Brown, a citizen of the United States of America, residing in Los Angeles, county of Los Angeles, and State of California, have invented a new, original, and ornamental Design for a Fishing Rod Holder Belt, of which the following is a specification, reference being had to the accompanying drawing, forming part thereof.

Fig. 1 is a front elevational view of a fishing rod holder belt, showing my new design.

Fig. 2 is a top plan view thereof on a reduced scale and with parts of the belt broken away, and

Fig. 3 is an end elevational view of the fishing rod holder belt shown in Fig. 2.

The dominant features of the design reside in the portion shown in full lines. The heavy dotted lines along the marginal edge and in the middle of the holder socket represent lines of stitching.

I claim:

The ornamental design for a fishing rod holder belt, substantially as shown and described.

ROBERT J. BROWN.
